UNITED STATES PATENT OFFICE.

EMORY BRADSHAW, OF UNIONVILLE, MISSOURI.

NON-REFILLABLE BOTTLE.

1,315,942.

Specification of Letters Patent. Patented Sept. 16, 1919.

Application filed July 17, 1918. Serial No. 245,369.

To all whom it may concern:

Be it known that I, EMORY BRADSHAW, a citizen of the United States, residing at Unionville, in the county of Putnam and 5 State of Missouri, have invented certain new and useful Improvements in Non-Refillable Bottles, of which the following is a specification.

This invention relates to containers, and 10 more particularly to non-refillable bottles.

The object of the invention is to provide a bottle of this character which may be readily emptied but may not be refilled, and the parts of which will not in any wise affect 15 the contents of the bottle.

Another object is to provide a device of this character which is simple and cheap to manufacture, thereby especially adapting it for use with cheaper grade materials as well 20 as with the more expensive kinds.

With the foregoing and other objects in view, which will appear as the description proceeds, the invention resides in the combination and arrangement of parts and in the 25 details of construction hereinafter described and claimed, it being understood that changes in the precise embodiment of the invention herein disclosed may be made within the scope of what is claimed without 30 departing from the spirit of the invention.

In the accompanying drawings:—

Figure 1 represents a vertical section through the upper portion of a bottle and its neck with this invention shown applied, 35 with the parts in the position which they assume before the removal of the cork when the bottle is in upright position,

Fig. 2 is a horizontal section taken on the line 2—2 of Fig. 1, and

Fig. 3 is a view similar to Fig. 1 with the cork shown removed and the bottle tilted for discharging its contents.

In the embodiment illustrated a bottle B is shown having the usual neck N which is 45 equipped on its interior near its connection with the bottle with an annular groove 1 for a purpose presently to be described. This bottle neck is also threaded interiorly at its inner end as at 2 to receive a threaded 50 stopper 3. This stopper 3 is made of glass or any suitable non-corrodible material, and has a bore 4 extending therethrough to receive an auxiliary stopper 10 presently to be described. The stopper 3 also is provided 55 with an annular series of longitudinally extending bores 5 arranged concentric with the

bore 4 which are designed for the discharge of the contents of the bottle when tilted as is shown in Fig. 3. The outer end of the stopper 3 is cupshaped to receive a correspondingly shaped head 11 of the auxiliary stopper or float 10. This float 10 is made hollow and of glass and the cup-shaped head 11 thereof has a shank 12 projecting inwardly from its convexed outer face and 60 adapted to be slidably mounted in the bore 4 of stopper 3.

A baffle plate 6 is mounted on the outer end of the stopper 3 and is concavo-convex in form, the periphery thereof being apertured as shown at 6^a to permit the free passage of liquid thereby when the bottle is tilted. The stopper 3 also has a groove 7 positioned to register with the groove 1 in the bottle neck when the stopper 3 is in operative position as shown in Figs. 1 and 3. Mounted in this registering groove is a packing 8 preferably composed of cork, although obviously it may be of any suitable material, and when inserted it will prevent 75 the removal of stopper 3.

A cork 9 is to be inserted in the outer end of the bottle neck N after the bottle has been filled, and the stopper 3 placed in position. When it is desired to remove the contents of 80 the bottle, all that is necessary is to take out cork 9 and to tilt the bottle in the position shown in Fig. 3, which will cause the auxiliary stopper or float 10 to move outward into the position shown in said figure thereby 85 opening the outer ends of the bores 5 which are normally closed by the cup-shaped head 11 of the member 10. The contents of the bottle will then flow out through the bores 5 past the head 11 and baffle plate 6 and be 90 discharged through the mouth of the bottle.

When the bottle is righted, the float 10 will drop back into the position shown in Fig. 1, thus closing the bores 5, protecting the contents of the bottle and preventing re- 100 filling thereof.

From the above description it will be obvious that a bottle equipped with this improvement will be entirely sanitary according to the nature of the material of which 105 the stopper and its coöperating parts are constructed.

The foregoing description and the drawings have reference to what may be considered the preferred or approved form of my 110 invention. It is to be understood that I may make such changes in construction and ar-

angement and combination of parts, materials, dimensions, etc., as may prove expedient and fall within the scope of the claimed invention.

5 Having thus fully described my invention, what I claim as new and desire to secure by Letters Patent, is:—

10 The combination with a bottle having a neck internally threaded near its inner end with an annular groove formed in said threaded portion; of a stopper threaded to engage the threaded portion of said neck and having a groove to register with the groove in the neck, a packing mounted in 15 said registering groove when the stopper is in operative position, said stopper having its outer end hollowed out in the form of a cup and provided with a centrally disposed bore

and a plurality of concentric bores disposed around said central bore, a baffle plate carried by the upper end of said stopper and apertured adjacent its periphery, and a cup-shaped float having a stem mounted to slide in the central bore of said stopper, said float normally overlying the concentric apertures of the stopper and closing them, the float being smaller than the baffle plate so that when the bottle is inverted, the contents may pass out through the concentric bores of the stopper and the apertures in said baffle plate. 25

In testimony whereof I affix my signature in presence of two witnesses.

EMORY BRADSHAW.
